UNITED STATES PATENT OFFICE.

E. J. GREEN, OF VALPARAISO, INDIANA.

IMPROVEMENT IN SPRING-BRACES AND CLIPS FOR CARRIAGES.

Specification forming part of Letters Patent No. 43,019, dated June 7, 1864.

To all whom it may concern:

Be it known that I, E. J. GREEN, of Valparaiso, in the county of Porter and State of Indiana, have invented certain new and useful Improvements in a Spring-Brace and Clip for Carriage Springs; and I do hereby declare the following to be a full, clear, and exact description of the same, reference being had to the accompanying drawings, making a part of this specification, in which—

Figure 1 represents a perspective view of so much of the parts of the carriage as will illustrate my invention. Fig. 2 represents a side view of the same, and Fig. 3 represents a section through the clip detached from the brace.

Similar letters of reference, where they occur in the separate figures, denote like parts in all the drawings.

The object and purpose of my invention is twofold. First, it is designed for keeping the spring in a perpendicular position, so that it will not sag by the pitching of the body of the carriage when the wheels run into, against, or over obstructions; and, secondly, in firmly securing the spring to the head-block by the spring brace and a clip combined.

Several devices have been essayed for bracing an elliptic spring to keep it in a perpendicular position; but they have failed to accomplish the purpose and are not in use, though such a thing is very much desired. The most common way is by a rod extending from the top of the spring and fastened to the rear of the carriage; but this allows the spring to work in the arc of a circle, and of course out of a perpendicular line, and the least variation from a vertical line increases rather than diminishes the evil. Toggle or elbow levers have been used also in connection with a brace or rod. The ordinary wear of such contrivances in a short time allows the spring to work out of its vertical line, and it pitches forward. So, too, a brace has been used with one foot of it fastened to the reach and the other foot to the spring and head-block, the brace being of an inverted V shape or form; but in this case the top of the brace is not supported, and will spring or yield, and thus allow the spring to play out of its vertical line.

My invention consists in an inverted, flaring, or U shaped brace, one foot of which is

fastened to the reach, and extending over and beyond the perch. Its other foot is fastened to the fifth-wheel or to a projection beyond the head-block, so that it will brace both ways, and in connection with this bow-shaped brace a vertical guide-rod, braced or secured at both its top and bottom, for the spring to move up and down by, thus forcing it to play in a vertical line; and my invention consists, secondly, in combining, with the bow-shaped brace and guide-rod for insuring a true vertical movement of the spring and preventing it from sagging, a clip for firmly holding the spring to the head-block.

To enable others skilled in the art to make and use my invention, I will proceed to describe the same with reference to the drawings.

A represents the reach of a carriage, to which is secured the head block B, upon which the spring C is supported.

D is a ring secured to the head-block and reach, and extending forward of the forward line of each. This ring constitutes a part of what is termed the "fifth-wheel."

E is an inverted-U or bow shaped brace which sets over the perch F and spring C, one of its legs being fastened, as at a, to the reach, and its other leg fastened, as at b, to the fifth-wheel D; or the reach may extend far enough in front of the head-block to receive this foot and fastening b.

G is a guide-rod, fastened at its upper end, as at c, to the crown of the brace E, and shouldered so as to rest upon the upper clip-plate, H, as at d, and fastened to the lower clip-plate, I, as at e, so that it stands in a vertical line and close to the spring C. To the top portion of the spring C, and at about its center, there is fastened a plate, f, having a hole through it, through which the guide rod G passes; and the spring in playing up and down must conform to the vertical position of this rod, which is fastened at both of its ends tightly, and thus avoids all shaking or loose motion.

The lower clip-plate, I, has one of its ends, g, bent up at right angles, and this bent-up end passes through the reach and through the top clip-plate, H, where it is secured by a nut, h, and by these plates and rod and bent end, and their supports and fastenings, the spring is firmly held to the head-block.

Having thus fully described my invention, what I claim therein as new, and desire to secure by Letters Patent, is—

1. In combination with the bow-shaped brace E, secured as herein described, the guide-rod G and guide-plate f, for keeping the spring in a vertical position as it plays under its superincumbent load, substantially as described.

2. In combination with the brace and the guide-rod, the clip-plates H I, for securely fastening the spring to the head-block, substantially as described.

E. J. GREEN.
